J. B. RAICH

WRENCH

Filed Dec. 5, 1924

John B. Raich
INVENTOR.

BY

George J. Metcalf

ATTORNEY.

UNITED STATES PATENT OFFICE.

JOHN B. RAICH, OF FORT WAYNE, INDIANA, ASSIGNOR, BY DIRECT AND MESNE ASSIGNMENTS, TO GEORGE GURALY, OF GARY, INDIANA.

WRENCH.

Application filed December 5, 1924. Serial No. 754,198.

The invention relates to wrenches and has for its object to provide a device of this character which may be easily and quickly adjusted for holding a nut by placing one jaw of the wrench upon the nut, and pushing inwardly on a slidable handle carried by the wrench, which slidable handle has a pinion and rack connection with a rack carried by a slidable shank, on the outer end of which the other jaw of the wrench is carried.

A further object is to provide clamping means cooperating with the rack of the shank of the outer jaw for holding said outer jaw in adjusted relation to the inner jaw after an adjusting operation.

A further object is to provide means whereby the slidable handle, during the adjustment of the jaws for various size nuts or other objects will be automatically extended or shortened for increasing or decreasing the leverage according to the size of the article held between the jaws.

A further object is to provide a wrench comprising an inner jaw having a shank, an outer jaw provided with a shank having a rack longitudinally slidable in a chamber of the shank of the inner jaw and an extensible slidable handle mounted on the shank of the inner jaw and provided with a rack opposite the rack of the jaw carried rack, and a pinion carried within the shank of the inner jaw and meshing with both of said racks, and forming means whereby upon an inward movement of the handle member, the jaws of the wrench will be brought together, and upon an outward movement the jaws will be moved apart, and at the same time the wrench shortened or lengthened.

A further object is to form its inner jaw and its shank from registering sections secured together, thereby allowing the parts to be assembled therein.

With the above and other objects in view the invention resides in the combination and arrangement of parts as hereinafter set forth, shown in the drawing, described and claimed, it being understood that changes in the precise embodiment of the invention may be made within the scope of what is

claimed without departing from the spirit of the invention.

In the drawing:

Figure 1 is a side elevation of a wrench, 55 showing the same extended in dotted lines.

Figure 2 is a bottom plan view of the wrench showing the handle in section on line 2-2 of Figure 1.

Figure 3 is a vertical longitudinal sectional view through the handle, showing the wrench mechanism with one side member of the inner jaw removed.

Referring to the drawing, the numeral 1 designates the inner jaw of the wrench and 2 the shank thereof. The jaw and shank 1 and 2 are formed from registering members 3, which are provided with a lug and groove connection 4 and 5 whereby the sections are maintained in registration, however the sections are also secured together by means of transversely disposed rivets 6. Slidably mounted within a longitudinally disposed chamber 7 of the shank 2, and which chamber has its lower end open is a rack 8, which is carried by the shank 9 of the outer jaw 10 of the wrench, and rotatably mounted within the chamber 7 on the shaft 11 is a pinion 12, which meshes with the rack 8, and which pinion 12 in turn meshes with a rack 13 secured to the inner side of a slidable handle 14, which is slidably mounted on the shank 2 carried by the jaw 1. It will be noted when the handle member 14 is forced inwardly with the jaw 1 in engagement with the nut or the like, the pinion 12 will be rotated by the rack 13, thereby imparting a movement on the rack 8 and shank 9, which carry the outer jaw 10 in the direction of the arrow a, therefore it will be seen that the outer jaw 10 will be quickly moved towards the jaw 1 for gripping the nut between said jaws, thereby obviating the use of adjusting screws and nuts as at present used on wrenches, consequently saving considerable time in adjusting the wrench. It will be seen that the jaws 1 and 10 may be easily and quickly moved apart for receiving nuts of larger size, and this is accomplished by imparting a rearward pull on the handle member 14, which action will cause the rack

95

100

13 to rotate the pinion 12 and force the shank 9 outwardly.

After the jaws have been properly adjusted in the manner above set forth, the same may be rigidly held by tightening the thumb screw 15, which is threaded through the shank 2 at 16 and which screw 15 is provided with a toothed member 17 pivoted to the inner end thereof, the teeth of which interengage with the teeth of the rack 8, consequently the shanks 2 and 9 are rigidly attached together, and at the same time with the shanks 2 and 9 rigidly secured together. With the shanks 2 and 9 rigidly secured together the pinion 12, which is carried by the shank 2 will be prevented from rotating, consequently the slideable handle member 14 will be prevented from movement longitudinally by the engagement of the rack 13 with the pinion 12, therefore it will be seen that the device through the single securing means 15 will be positively held in adjusted position, and at the same time may be easily released by the rotation of the thumb screw 15. It will be noted that as the jaws 1 and 10 are moved apart, the slideable handle member 14 is automatically extended for increasing the leverage as the size of the nut to be re-

ceived between the jaws 1 and 10 is increased, and as the jaws 1 and 10 move together the slideable handle member 14 moves inwardly, thereby decreasing the leverage and shortening the wrench as a whole for use upon small nuts. Also the wrench will answer the purposes of several sizes of wrenches, and will obviate the necessity of a mechanic having a multiplicity of sizes of wrenches.

The invention having been set forth what is claimed as new and useful is:—

A wrench comprising an inner jaw, an outer jaw, a chambered shank carried by the inner jaw, a shank carried by the outer jaw and slidably mounted in the shank of the inner jaw and entirely housed in the shank of the inner jaw, a gear rotatably mounted within the shank of the inner jaw, a rack carried by the shank of the outer jaw and meshing with said gear, a chambered handle member slidably mounted on the shank of the inner jaw and entirely housing one end thereof and a rack bar carried by the inner side of the chambered handle and slidably mounted within the shank of the inner jaw.

In testimony whereof I affix my signature.

JOHN B. RAICH.
